UNITED STATES PATENT OFFICE.

ALAN R. FERGUSSON, OF BUFFALO, NEW YORK.

TOY RAILWAY CROSSOVER.

Original application filed February 3, 1923, Serial No. 616,647. Divided and this application filed April 17, 1923. Serial No. 632,602. Renewed December 5, 1923.

To all whom it may concern:

Be it known that I, ALAN R. FERGUSSON, a citizen of the United States, residing at Buffalo, in the county of Erie and State of New York, have invented certain new and useful Improvements in Toy Railway Crossovers, of which the following is a specification.

This invention relates to crossovers for miniature or toy railways, and is a division 10 of my co-pending application Serial No. 616,647, filed February 3, 1923, for toy railway crossovers.

An object of this invention is to provide 15 an improved crossover adapted to be easily and effectively connected or joined to a plurality of toy track sections, and which will be relatively cheap and easy to manufacture, strong, durable and efficient in use 20 and operation.

A further object of this invention is to provide a toy or miniature crossover section for a sectional toy or miniature railway, and wherein the crossover is provided with 25 wire-formed rails, and wherein the crossover section together with the adjacent sections of the toy railway, form a portable structure adapted to be readily and easily assembled and knocked down.

30 A further object of this invention is to provide a toy railway crossover section having wire-formed rail members forming frog points, and also having intermediate rail portions stamped up from a single piece of 35 sheet metal, the construction being such as to form a durable and strong crossing member.

A further object of this invention is to 40 provide a toy railway crossover having means for releasably connecting certain of the rail ends thereof to the rail ends of adjacent track sections, and wherein certain of the rail ends are adapted to be tensioned or contracted to form a spring or tension 45 joint.

A further object of this invention is to 50 provide an improved toy or miniature crossover having means readily adapted to permit the attachment of a detachable third or power rail thereto, and also having improved means for transmitting the current from a power rail at one side of the crossover to a power rail at another side thereof.

Other objects of this invention will appear 55 in the following description and ap-

pended claims, reference being had to the accompanying drawings forming a part of this specification, wherein like reference characters indicate corresponding parts in the several views, and wherein Fig. 1 is a 60 plan view illustrating my invention; Fig. 2 is a bottom plan view partly broken away illustrating the same; and Fig. 3 is a perspective view illustrating a part thereof.

Before explaining in detail the present 65 improvement and mode of operation thereof, I desire to have it understood that the invention is not limited to the details of construction and arrangement of parts which are illustrated in the accompanying drawings, 70 since the invention is capable of other embodiments, and that the phraseology which I employ is for the purpose of description and not of limitation.

The construction shown in the drawings 75 is for a right angled crossover, but it will be understood that my invention is not limited to this form of crossover, but the parts thereof may be located at any desired angle or inclination.

The present improved crossover comprises in general a base or supporting plate previously cut to the required shape and form from a piece of sheet metal and stamped up or otherwise formed with spaced intermediate rail portions or ribs. Mounted upon this supporting plate in proper relation to the bent-up rail ribs are a plurality of cylindrical or wire rail members forming oppositely located frog points. The ends of 85 these wire rail members are preferably provided with means for releasably connecting the same to the rails of adjacent track sections, and in the present instance this means is adapted to form releasable spring joints 90 with juxtaposed wire rails of the adjacent sections. As a result of the foregoing construction, a crossover or toy railway crossing frog may be provided at a minimum of expense, due to the fact that the amount 95 and cost of material used is reduced considerably as well as the number of steps in the operation of forming the crossover.

The crossover in the present instance is 100 formed with four radiating arms 9 of similar construction and located at an angle to each other, herein shown at right angles to each other for the purposes of illustration. The crossover is provided with a central 105 supporting plate or base 10 having the cen-

tral portion thereof cut away at 11 and the edges thereof bent up or partially coiled to form spaced intermediate rail portions or ribs 12 located at an angle to each other. 5 To each corner portion of the plate 10 is secured, as by welding, a wire, which is preferably slit substantially midway thereof and bent to form a frog point 13, and a pair of rail members 14 and 15. The rail members 14 of opposite arms of the cross-over are located in alinement with each other, and also with a rail member 12, so that these parts form a continuation of the alined rails of the track sections, which are 10 15 connected to the crossover.

It will be seen that the frog points 13 terminate substantially midway between the spaced adjacent ends of rail ribs or members 12, and are spaced therefrom so as to 20 permit the flanges of the car wheels to pass unobstructed over the rails of the crossover in transverse directions.

To the outer end of each companion pair of rails 14 or 15 is secured a clamping member or guide plate 16. Each guide clamp 16 is provided at the lateral edges thereof with upwardly curved guide portions 17 adapted to receive the ends of the wire rails 14 or 15, the portion 17 being preferably 25 bent up or partially coiled to conform to the shape of the wire or cylindrical rails, and the ends of the latter are preferably spot welded thereto, as shown at 20. The guide portions 17 of each clamp plate project a 30 suitable distance beyond the ends of the wire rails 14, so as to receive the free spring ends 18 of an adjacent track section 19 and be interlocked therewith. In the present instance, the interlocking connection or joint 35 is substantially a spring or tension joint, and preferably includes lugs or projections 21 pinched outwardly from the ends of the rails 18 and adapted to be inserted into openings 22 in the guide portions 17. In 40 order to connect these parts, it is necessary to contract or tension one or both of the ends of the rails 18 so as to permit the lugs 21 to clear the guide portions 17 and to 45 spring into the openings 22. Each section 50 19 preferably comprises wire ties 23 for supporting the wire rails 18 and to which the rails are preferably spot welded, thereby providing a rigid, durable and cheap construction. It will be understood of course 55 that track sections similar to section 19 may be releasably connected to the other arms of the crossover in the same manner as above described.

Where it is desired to utilize the crossover 60 with an electrical toy railway, the same is provided with suitable terminal connections for transmitting power between the opposed third rails. In the present instance the terminal connecting means comprises a 65 piece of sheet metal cut to the required

shape and stamped up to form a central raised or hollow portion 24 adapted to extend into the central opening 11 in the plate 10. This hollow projecting portion 24 is provided with a plurality of radially extending arms 25, which extend in opposite directions across the underside of the base plate 10. Between the arms 25 and the base plate is interposed a suitable strip of insulating material 26, and the arms 25 are 70 each provided with lugs 27, which are clinched over the side edges of the plate 10. Intermediate the lugs 27 each arm terminates in a spring contact member 28, and when the third rail 29 is located in position 75 the end of the third rail will bear down against spring contact member 28. In this manner the current will be transmitted between the separated ends of the opposed third rails. 80

It will be seen that the insulating strip 26, which is interposed between the terminal connector 24-25 is provided at opposite sides thereof with projecting portions 30, which are folded over the edges of the plate 10 and extend over upon the upper surfaces thereof, the lugs or tongues 27 being clinched over the insulating portions 30 so as to hold the same in position. 85

Where the crossover is used with an electrical toy railway, a wire-formed third rail 29 is detachably connected to each arm 9 of the crossover, the detachable connection with each arm being accomplished in the present instance by means of a spring clip 90 31. The clip 31 preferably comprises a channeled portion or gutter formed by curved side walls 32 into which the wire 29 may be sprung and also readily released. This clip is bent under at its end to form a 95 hook portion, which may be hooked over the notched edge 33 of the clamp plate 16, and a suitable strip of insulating material 34 is interposed between the clip 31 and the plate 16, the ends of the strip being folded 100 under and interposed between the bent end of the clip 31 and the bottom of the plate. A further detailed description of this construction is not believed to be necessary herein, as the same is fully described in my 105 110 said co-pending application, of which this is a division. 115

It will be noted that when the third rail 29 is inserted in the gutter formed by the spring walls 32 of the clip 31 and the latter is connected, as shown in Fig. 1 to the clamp plate 16, the end of the third rail will project beyond the clip and engage the spring contact member 28 of the terminal connector, and when other third rails are 120 125 in like manner in position upon all the arms of the crossover, the current will be transmitted by means of the terminal connector from one power rail to the other underneath the crossover. 130

It is to be understood that by describing in detail herein any particular form, structure, or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A toy crossover comprising a plurality of wire-formed rail members terminating in a frog point.

2. A toy crossover comprising a plurality of wire rails bent to form frog points.

3. In a toy railway, the combination of a supporting member, and a plurality of wire rails secured thereto and forming oppositely located frog points.

4. In a toy crossover, the combination of a supporting plate, and a plurality of wires bent to form angularly related rails and frog points.

5. In a toy railway, the combination of a supporting member, and a plurality of wire rails secured thereto and forming oppositely located frog points, said member having bent up rail portions.

6. In a toy crossover, the combination of a supporting plate, and a plurality of wires bent to form angularly related rails and frog points, said plate having bent up rail portions spaced from said frog points.

7. A toy crossover comprising a sheet metal plate bent or stamped up to form a plurality of rail portions, and a plurality of angularly located wire rails carried by said plate.

8. A toy crossover comprising a sheet metal plate having certain edges thereof bent or coiled to form rail portions, and wire rail members carried by said plate and terminating in frog points adjacent to said rail portions.

9. A toy crossover comprising a supporting plate, and a plurality of opposed wire crossing frogs carried by said plate, said plate having rail portions intermediate said frogs.

10. A toy crossover comprising a supporting plate, and a plurality of opposed wire crossing frogs carried by said plate, said plate having bent up rail portions intermediate said frogs and extending in continuation of parts thereof.

11. A toy crossover comprising pairs of wire rail sections having a plurality of intersecting points, a plate connected thereto and having a part bent to form rail portions intermediate said intersecting points.

12. A toy crossover comprising pairs of wire rail sections having a plurality of intersecting points, a plate connected thereto

and having a part bent to form rail portions intermediate said intersecting points, said plate having a central opening, and a terminal connector having a part thereof extending upwardly through said opening.

13. In a toy railway, the combination of a plurality of wire track sections, a crossing member having intersecting wire track sections, and means for releasably connecting certain of said sections together.

14. In a toy railway, the combination of a plurality of wire track sections, a crossing member having intersection wire track sections, and means for releasably connecting certain of said sections together and forming a spring joint.

15. In a toy railway, the combination of a track section comprising a pair of spaced wire rails, and a crossing member having wire rails and adapted to be releasably connected to said section.

16. In a toy railway, the combination of a section comprising a pair of spaced wire rails having wire-formed supporting means, and a crossing member having wire rails and adapted to be releasably connected to said section.

17. In a toy railway, the combination of a crossing member having wire-formed rails, and a power rail detachably connected thereto.

18. In a toy railway, the combination of a crossing member having wire-formed rails, and a wire power rail detachably connected thereto.

19. In a toy railway, the combination of a track section having a wire rail, a crossing member having a wire rail adapted to be located in substantial prolongation with said first wire rail, and means for releasably connecting said wire rails together.

20. In a toy railway, a crossing member comprising a wire rail terminating in a clamping member, and a wire rail detachably connected to said clamping member.

21. In a toy railway, the combination of a crossing member having wire rails, and a track section adapted to be detachably connected to said crossover and comprising wire ties and wire rails connected thereto.

22. In a toy railway, the combination of a crossing member, a terminal connector having spring contact portions projecting at opposite sides of the crossover, and a wire rail releasably connected to said crossover and engaging one of said contacts.

23. In a toy railway, the combination of a crossing member, and a terminal connector extending crosswise beneath said member and having terminal spring contacting portions.

24. A toy railway crossover comprising supporting means, wire traction rails, and a wire power rail.

25. A toy railway crossover comprising

supporting means, wire traction rails, a wire power rail, and a rail portion formed from said supporting means.

26. In a toy railway, a crossing member comprising a wire rail, a track section comprising a wire rail, and clamping means for releasably connecting said rails end to end.

27. A crossing member comprising supporting means, and wire rails welded thereto.

Signed at Buffalo, New York, this 12th day of April, 1923.

ALAN R. FERGUSSON.
